UNITED STATES PATENT OFFICE.

JACOB HÜRLIMANN, JR., OF WÄDEN SCHWEIL, SWITZERLAND.

SOLDERING-IRON.

SPECIFICATION forming part of Letters Patent No. 650,643, dated May 29, 1900.

Application filed December 20, 1899. Serial No. 740,962. (No model.)

To all whom it may concern:

Be it known that I, JACOB HÜRLIMANN, Jr., a citizen of Switzerland, residing in Wäden-schweil, canton of Zurich, Switzerland, have 5 invented certain new and useful Improve-ments in Soldering-Irons; and I do hereby declare the following to be a full, clear, and exact description of the invention, such as will enable others skilled in the art to which 10 it appertains to make and use the same, ref-erence being had to the accompanying draw-ings, and to letters and numerals of reference marked thereon, which form a part of this specification.

15 This invention relates to soldering-irons; and it has reference particularly to that class of such implements in which is comprised in the device a receptacle for the solder, which latter may be maintained in a molten condi-20 tion by heating the receptacle, and, in com-bination with said receptacle, means for feed-ing or discharging the solder therefrom.

25 The object of the invention is to provide an improved tool of the kind above particularly designated and which shall be simple and durable in construction and thoroughly effi-cient in operation.

30 The invention consists in the improved soldering-iron and in the combination and ar-rangement of its various parts, substantially as will be hereinafter pointed out, and finally embodied in the clauses of the claim.

35 Referring to the accompanying drawings, in the two figures of which corresponding let-ters and numerals of reference indicate like parts, Figure 1 is a view in side elevation of my improved soldering-iron, a portion thereof being shown in section; and Fig. 2 is a top plan view of my improved soldering-iron, the 40 handle and part of a certain lever being broken away.

In said drawings, *a* designates a metallic 45 receptacle or chamber which is substantially cylindrical in form and to which is secured, preferably by a tongue-and-groove joint *b*, a tip or head *c*, formed, as usual, of copper and adapted for use in manipulating the solder after it has been applied. Into the bottom wall *d* of the receptacle or chamber *a* projects 50 the lower end of a tube *e*, which is screw-threaded, as at *f*, and engages corresponding screw-threading in said wall *d*. The main

bore *g* of this tube is reduced near its lower end, where it consists of a channel *h*, which communicates with another channel *i*, that is 55 formed in the tip or head *c*, penetrating the same. At the point where the bore *g* of the tube merges into the channel *h* two or more radial ducts *j* extend through the wall of the tube, thereby affording communication be-6c-tween the interior of the chamber *a* and said channel *h*.

Into the top of the chamber *a* is screwed a cap *k*, said cap thus being removable. Into said cap is set a screw *l*, which constitutes a 65 plug. This plug may be removed, so that the threaded opening into which it fits can be adapted not only for filling the chamber with solder, which can be most conveniently introduced in molten form, but it is also 70 adapted as an air-vent should it be necessary to provide for the escape of the air at any time, as when in melting the solder in the chamber.

It should be remarked that the upper end 75 of the tube *e* fits into a recess *m* in the under side of the cap *k*.

n designates a valve-stem having at its lower end a tapered plug *o*, which is adapted to seat in the bottom of the bore *g* to thus 80 close communication between the ducts *j* and the channel *h*.

The cap is provided on its outer face with an integral hexagonal projection *p*, and through this projection and the cap extends the upper 85 end of the valve-stem *n*. The valve-stem before it projects through the cap has a threaded enlargement *q*, which is screwed into the upper end of the tube *e*. Thus by turning the valve-stem longitudinal adjustment thereof 90 can be effected, and in this way the commu-nication between the interior of the chamber *a* and the channel *h* can be controlled. The hexagonal enlargement *p* of course is pro-95 vided, so that with the use of a wrench the cap can be readily fixed in place or removed. The upper end of the valve-stem is provided with a crank *r*, whose free end carries a screw *t*. Said screw serves as a pivotal connection be-tween the connecting-rod *u* and said crank. 100

v is a spindle or shank which at one end is screwed into an enlargement *w*, projecting laterally from the upper end of the chamber *a*, and which at the other end carries a han-

dle *x*. Upon the handle is fulcrumed on a stud *y*, projecting therefrom, a bent lever *z*, one of whose ends extends in convenient reach of the handle *x* and the other of whose ends is pivotally connected through the medium of a pin *z'* with the free end of the connecting-rod *u*.

The connecting-rod works in an arm or bracket 2, which is screwed into the spindle 10 or shank and projects laterally therefrom, and the connecting-rod is normally forced toward the handle end of the implement by means of a spiral spring 3, which is coiled about it and is disposed between the bracket 15 2 and the collar 4, secured on said connecting-rod. The action of the spring of course tends to normally close the valve which controls the discharge from the chamber *a*.

It is believed that the operation of my improved soldering-iron will be fully understood without particular description thereof.

Having thus fully described my invention, what I claim as new, and desire to secure by Letters Patent, is—

25 1. In a soldering implement, the combination of a hollow member having a suitable discharge outlet or outlets, a valve controlling said outlet or outlets and having a screw-threaded engagement with a rigid portion of 30 said member, a handle projecting from said member, and means, carried by said handle,

for turning said valve, substantially as described.

2. In a soldering implement, the combination of a chamber or receptacle, a handle projecting therefrom, a tube inclosed in said receptacle, said tube having openings affording exterior communication from said chamber, a valve-stem screwed into said tube and having a plug adapted to control said openings, and means, carried by said handle, for turning said valve-stem, substantially as described.

3. In a soldering implement, the combination of a chamber or receptacle, a handle projecting therefrom, a tube inclosed in said receptacle, said tube having openings affording exterior communication from said chamber, a valve-stem screwed into said tube and having a plug adapted to control said openings, a cap for said receptacle, said valve-stem projecting through the same, a crank carried by the exterior end of said valve-stem, a lever fulcrumed on the handle, and a spring-actuated rod connecting the lever and the crank, substantially as described.

In testimony that I claim the foregoing I have hereunto set my hand this 5th day of December, 1899.

JACOB HÜRLIMANN, JR.
